UNITED STATES PATENT OFFICE

SIGVART BAARDSETH, OF CORONATION, ALBERTA, CANADA

ADJUSTABLE PUMP JACK BALANCE

Application filed May 26, 1931. Serial No. 540,181.

This invention appertains to new and useful improvements in pump jacks, and more particularly to an adjustable balance of pump jacks.

5 The principal object of the invention is to provide a pump jack balance adapted to increase the efficiency of a pump jack thereby requiring less power to operate the same.

Other important objects and advantages of 10 the invention will become apparent to the reader of the following specification and claim.

In the drawings:—

Figure 1 represents a fragmentary top plan 15 view of the pump jack and balance.

Fig. 2 represents a fragmentary side elevational view showing the pump jack and balance.

Fig. 3 represents an enlarged fragmentary 20 detailed sectional view taken substantially on the line 3—3 of Fig. 2.

Fig. 4 represents an enlarged fragmentary detailed sectional view taken substantially on the line 4—4 of Fig. 2.

25 Referring to the drawings wherein like numerals designate like parts, it can be seen that numeral 5 represents a frame upon which the bearings 6 are mounted to generally receive the shaft 7 carrying the pinions 8—8, which mesh with the gears 9—9 on independent stub shafts journaled in the bearings 10 on the frame 5.

The conventional power plant is generally referred to by numeral 11 and drives the shaft 35 7 in the usual conventional way by the belt 12 and pulleys 13. Each of the gears 9 has an eccentrically mounted pin 14 projecting outwardly therefrom, and each of these pins is loosely disposed through the lower end of a pitman 15, the upper end of the pitmen being secured as at 16 to the horizontal bar 17 which in turn is secured as at 18 to the pump rod 19.

In particularly carrying out the present 45 invention, an elongated arm 20 is secured fixedly at one end to the outer end of one of the pins 14 and it may be necessary that this end portion of the arm be offset at approximately the point 21 to avoid any projecting 50 elements of the pump machinery.

The arm 20 is provided with a plurality of longitudinally spaced openings 22 and a weight body 23 having an opening therethrough to receive the arms 20, is slideable on the said arms, and is further provided with 55 a support to accommodate a bolt 24 which can be engaged thru any one of the openings 22, to fix the weight body in any adjusted position on the arm 20.

A nut 25 is engageable on the bolt 24 to prevent displacement of the bolt from the weight body. As is clearly shown in Fig. 4, the inner end of the arm 20 may be provided with a polygonal-shaped opening to receive the polygonal-shaped portion 26 of one of the 65 pins 14, thus preventing rotation of the arm independently of the pin.

It can thus be seen, that with the weight on the arm and the arm projecting from the gear on the eccentric pin, the pump jack, will be, 70 mechanically speaking, balanced, thus making it possible to operate the jack on less power than conventional jacks of the same horsepower capacity.

While the foregoing specification sets forth 75 the invention in specific terms, it is to be understood that numerous changes in the shape, size and materials may be resorted to without departing from the spirit and scope of the invention as claimed hereinafter. 80

Having thus described my invention, what I claim as new is:—

In a pump jack, a pump jack wheel, an eccentrically mounted pin on the wheel projecting laterally therefrom, said pin being of 85 polygonal shape at its portion beyond the wheel and being journaled at its remaining portion through an opening in the wheel, the projecting portion of the pin being engageable with the usual pump jack connecting rod, an elongated arm having a polygonal-shaped opening at one end for receiving the polygonal shaped portion of the pin, a slideable weight on the arm and means between the weight and the arm whereby the weight can 90 be adjusted on the arm.

In testimony whereof I affix my signature.

SIGVART BAARDSETH.
